FIG. 6

WORD PLUS WORD GAME

SUMMARY OF THE INVENTION

My invention is directed toward a word-plus-word game—leading into phrases and sentences designed to encourage the ridiculous, the paradoxical, the absurd, the preposterous and even the sensible thoughts that may come to mind as the game progresses.

This game employs a message sheet carrying a plurality of messages each containing the same number of words, as well as various types of playing pieces, markers and chips carrying message words and/or numbers or carrying legends described in detail and used as set forth below.

Messages and game parts can be carried as stock items for individuals who wish to enlarge the game after original purchase. This feature enables manufacturers and retailers to increase sales above such attributed to sales of the games in original form.

BRIEF DESCRIPTION OF THE DRAWINGS

In the drawings:

- FIG. 1 shows the master sheet;
- FIG. 2 shows opposite sides of a wood-word piece;
- FIG. 3 shows a wood-O piece;
- FIG. 4 shows S point markers;
- FIG. 5 shows roll-chips; and
- FIG. 6 shows commpoint pieces.

DETAILED DESCRIPTION OF PREFERRED EMBODIMENTS

Referring now to FIGS. 1-6, the game which I call GET THE MESSAGE (Good Thinking) employs the following parts or components:

GAME PARTS

1. THE MASTER SHEET 100 (Note: - Not seen by players until end of game).

A sheet of paper or cardboard on which is printed twenty messages 102 directly under each other—doublespaced.

Each message is in twelve words. Above each word 104 is a number. The first word is number one and so on until number twelve.

Preceeding the first word is another code number which will be used later to identify that particular message.

2. "WOOD WORD" - "N-point - M-word"

Two hundred and forty domino sized wood pieces 106. Each piece is known as a "wood-word". Since all the messages are twelve words long then twelve "wood-words" are used to recreate the message. Each "wood-word" has one of the numbers from one to twelve on one side and the corresponding message word on the other.

The side with number is called an "N-point".

The side with word is called an "M-word".

3. wood-O

Forty-eight domino sized wood pieces 108. Each piece bearing one of the numbers from one to twelve - repeated four times - that is - four number ones, four number two's and so on until twelve. The other side of this piece is blank. This piece will be known as a "wood-O". (Note: - a "wood-O" becomes a "P-word" word during course of game.)

4. S-point

5

5. "ROLL-CHIP":

Forty-eight colored chips 112 - each having one of the numbers from one to twelve. This chip is called a "roll-chip".

10 6. "COMMPOINT"

One hundred and forty-four domino sized wood pieces 114 with one of the following on each piece - (the other side is blank):

15

	comm	repeated on sixteen pieces
	commu	do.
	commun	do.
	communi	do.
	communic	do.
	communic	do.
	communicat	do.
	commicate	do.
20	Good Thinking	do.

These pieces to be used in scoring are called "comm-points".

25 7. Five blank pads

8. Five pencils with light lead

9. Art Gum eraser

10. One pair dice

30

SUMMARY OF TERMS USED

1. Master Sheet

a 9 x 10 inch sheet of paper - or - cardboard on which is printed 20 messages, directly under each other. Each message is in 12 words.

35 2. Wood-word

A domino sized piece of wood bearing one of the numbers from 1 to 12 on the back and in front with one of the words from the Master Sheet.

3. N-point

The number from one to twelve on back of a wood-word.

4. M-word

The word on other side of "N-point".

45 5. C-word

A Number one wood-word bearing on the "m-word" side - lower right hand corner - the identifying code number used to verify an O.K. Message.

6. wood-O

A domino sized piece of wood with one of the numbers from 1 to 12 on one side and blank on the other. (Note: A wood-O becomes a wood-word during course of game.)

7. P-word-word

A wood-O that has become an M-word and is used for scoring.

8. S-point

A marker or chip with one of the numbers from 1 to 30 on it.

9. Roll-chip

A colored marker or chip with one of the numbers from 1 to 12 on it.

60 10. Commpoint

A domino sized piece of wood - blank on one side and on the other side with one of the following - "comma", "commu", "commun", "communi", "communic", "communic", "communient", "communi-
cate" - "Good Thinking".

11. "Good Thinking"

Signifying that a player has earned all of the comm-points ranging from "comm" to "Good Thinking".

12. Message

Any phrase or sentence formed by using ANY combination of wood-words during the course of a game by a player.

13. Declared Message

Any 12 word sequence using wood-words in 1 to 12 sequence that a player declares is one of his quote messages. (Note: All wood-words on a Declared Message are retired from game.)

14. Non-Declared Message

Any 12 word sentence using wood-words IN or OUT of point-number sequence—used for point scoring only. (Note: All wood-words on Non-Declared Messages are reusable always.)

15. N. G. Message

Any sentence formed by using any combination of wood-words without regard to the point-number sequence and only using 12 wood-words. Also any 12 word sentence using wood-words in consecutive order from 1 to 12 that does not agree with Master Sheet.

16. Good Thinking Message

Any 12 word sentence using wood-words IN or OUT of sequence used to complete a "comm" to "Good Thinking" sequence. Worth only 50 points no matter what the point-numbers add up to. (Note: all wood-words on Good Thinking Message are re-usable always.)

17. O.K. Message

Any 12 "M-word" message made during course of game that is the same as a message on the Master Sheet.

MEANING OF INITIALS

C = check
O = open

N = number
P = players

M = message
S = score

SCORING OF POINTS

SCORING

Points are earned by forming a grammatically correct sentence or phrase from any combination of wood-words accumulated during the course of the game.

Players will decide ONLY IF A SENTENCE OR PHRASE IS GRAMMATICALLY CORRECT AND NOT DECLARE IT VOID BECAUSE—"IT MAKES NO SENSE."

The purpose being to encourage the ridiculous, the paradoxical, the absurd, the preposterous and even the sensible thoughts that may come to mind as the game progresses.

WAYS TO GET POINTS

1. By adding up the N-points on the wood-words used to make approved sentences or phrases.

2. By making commpoints for originating an approved sentence or phrase consisting of 4 words or more—with the following values:

For 4	word sentence or phrase (approved)	"comm"	25 points
For 5	do.	"commu"	25 points
For 6	do.	"commun"	25 points
For 7	do.	"communi"	25 points
For 8	do.	"communie"	50 points
For 9	do.	"communica"	50 points
For 10	do.	"communicat"	50 points
For 11	do.	"communicate"	50 points
For 12	do.	"Good Thinking"	50 points

The accumulation of the nine commpoints going from "comm" to "Good Thinking" is worth an additional 100 points—making a total of 450 points. (Note: A "Good Thinking" message is worth 50 points if it is being used to complete a "comm to good-thinking" sequence. If a player decides against using a "Good Thinking" message as unit in a "comm to good-thinking" sequence he can add up the N-points of the wood-words in his "Good Thinking" message for his score.—He cannot use that same message later on in the game for his sequence use.

3. By reproducing what turns out to be an O.K. Message.

An O.K. Message is worth 500 points.

An N.G. Message is worth only 75 points (To discourage players from too quickly announcing and showing a Declared Message which he hopes will be the O.K. one).

WHAT TO REMEMBER (In Scoring of Points)

a. All wood-words in any declared message are retired from the game.

b. All wood-words, except those used in a Declared Message can be used again and again until games end. Including wood-O's that have become wood-words. (See Playing of Game)

c. Point count is kept by using Roll-chips and comm-points. All commpoints have their values printed on them.

d. wood-O's that have become wood-words (see Playing of Game) cannot be used to make a Declared Message.

e. Even the changing of but one word in a message already used will earn Roll-chip points.

f. To keep the table clear for more playing room players can keep record of messages that have earned points on pads provided at beginning of game.

g. A player cannot take both Roll-chips and comm-points for the same message.

h. Sentences where Question Marks would be used are eligible for points.

i. Duplication of other players messages not permitted.

GAME IS OVER

1. When a player creates 4 messages (4 player quota) that he feels are O.K. Messages. He can show his Declared Messages (which he now thinks will be O.K.) one at a time or spring all four at one time.

2. When a player has gathered 4 sequences from "comm to good-thinking".

3. When there is a stalemate in Buying, Selling and Trading of wood-words (See How to Play Game).

THE WINNER

60 The player who has earned the most points. Not al-

ways the one who ends game with messages or comm-point sequence.

REMEMBER WHEN GAME IS OVER FOR ANY OF THE ABOVE REASONS POINTS ARE THEN ADDED UP AS NOT ALL DECLARED MESSAGES ARE O.K. MESSAGES. 5

HOW TO PLAY - GET THE MESSAGE (Four Players)

(Note - Players do not read or see any of messages on 10 Master Sheet before game begins)

1. Each Player takes pad and pencil.
2. All 240 pieces of wood-words are placed in center of table and scrambled with N-point number face up. 15

3. Each player then picks 12 wood-words from table and places them in front of him with "M-word" side facing him.

4. Then the 48 wood-O's are mixed in with the wood-words - point number side face up.

5. The S-points, Roll-chips and Commpoints are placed separately face-up on the table but away from playing area and within reach of players.

6. Play now begins

a. First player rolls dice. The number that comes up is the wood-word number that the player takes from the table. He also takes that same number from the roll-chips. This roll-chip number is to show the other players and the player himself that he has already rolled that number.

Player rolls again. If same number comes up as proven by roll-chip in front of player he loses turn. If different number, he repeats process as with first number - and continues playing, as long as he rolls a different number. NOTE: If player rolls a number that turns out to be a wood-O he rolls again.

When player has lost his turn he then sets himself to creating messages.

A PLAYER CAN USE HIS WOOD-O TO WRITE ON ANY WORD HE WANTS TO USE FOR A MESSAGE.

When his turn comes up again he presents his message (only one) to the players for approval—before rolling dice.

When a message is approved the player takes the S-point, equivalent (see Scoring of Points) from the S-point or Commpoint pile.

b. The next three players will follow same procedure as the first player.

c. When play comes around again to first player he continues to roll for a number that he has not made. The roll-chips in front of player is the means of checking.

When any player has made all the numbers (Roll-chips) from 1 to 12 - in any order - he puts the Roll-chips back on the table and begins all over again.

NOTE: The number one Roll-chip is picked when the player rolls a one from a single dice. The player may roll for this Number one at any time during his turn. AS IN SCORING OF POINTS - REMEMBER ANY WOODWORD USED IN A 65

MESSAGE CAN BE USED AGAIN AND AGAIN UNTIL END OF GAME.

BUY, SELL, TRADE:

d. When all the wood-words have been taken from table then players will expose at any time, any wood-word they think they can spare and offer to Buy, Sell, or Trade with any other player for a wood-word, they think will help in creating other messages or with a view towards ending game.

Players will continue to Score Points after Buying, Selling or Trading and can at any time offer to Buy, Sell or Trade any wood-word not previously exposed.

GAME IS OVER AS EXPLAINED IN POINT SCORING

NOTE: Words on wood-O's erased or washed off before beginning new game.

While I have described my invention with particular reference to the drawings, such is not to be considered as limiting its actual scope.

Having thus described this invention, what is asserted as new is:

1. A word plus word game leading into phrases and sentences which comprises:
- a master sheet containing a plurality of messages disposed one below the other, each message containing a like number of words, each word being identified by the number which identifies its sequential position in the message, the first word in the message being identified by the number one and so on;

- a plurality of first wood-word pieces, each having a message word on one side and the number identifying this word on the other side;
- 5 a plurality of second wood pieces, each having a different one of the identification numbers thereon;
- a plurality of markers, each having a different one of numbers from one to thirty inclusive thereon;
- 10 a plurality of chips, each having a different one of the numbers which identifies the position of a message word thereon; and
- 15 a plurality of third commpoint pieces, each third piece having one of the following thereon: comm, commu, commun, commune, communic, communica, communicat, communicate, and Good Thinking.
2. The game of claim 1 employing twenty messages of twelve words each.
  3. The game of claim 2 wherein there are forty-eight second pieces divided into four like groups of twelve, each piece in each group carrying a different number from one to twelve inclusive.
  - 20 4. The game of claim 3 wherein the chips are divided into four like groups of twelve, each piece in each group carrying a different number from one to twelve inclusive.
  5. The game of claim 4 wherein there are one hundred and forty-four commpoints divided into nine groups of sixteen, each group being assigned a different one of the legends recited in claim 1.
  - 25 6. The game of claim 5 wherein additional messages and game parts can be added.

* * * * *
